UNITED STATES PATENT OFFICE.

PHILIP FISCHBACHER, OF QUINCY, ILLINOIS, ASSIGNOR TO AMERICAN SANITARY REFRIGERATION CO., OF OWENSBORO, KENTUCKY, A CORPORATION OF DELAWARE.

REFRIGERATING-MACHINE.

1,389,747.

Specification of Letters Patent. Patented Sept. 6, 1921.

Original application filed July 30, 1919, Serial No. 314,222. Divided and this application filed July 12, 1920. Serial No. 395,490.

To all whom it may concern:

Be it known that I, PHILIP FISCHBACHER, a citizen of the United States, residing at Quincy, in the county of Adams and State 5 of Illinois, have invented certain new and useful Improvements in Refrigerating-Machines, of which the following is a specification, reference being had to the accompanying drawings.

10 This invention relates to refrigerating machinery of that character wherein an element under pressure is allowed to expand within the refrigerating coils, is then withdrawn therefrom to a compressor and is compressed therein, and then condensed and then passes back through the expansion or refrigerating coils, and particularly to a condenser whereby the gas is condensed after leaving the compressor, this application 15 forming a division of my application filed on July 30, 1919, Serial #314,222, on refrigerating machines.

One of the objects of the present invention is to improve the construction of the condenser by providing means whereby cooling water or other liquid in the condenser may be kept cool by the passage of air through cooling tubes passing through the water and by the aid of fins forming part of the water 20 containing tank.

Another object is to provide means for forcing air through these tubes and against the condenser jacket.

Other objects will appear in the course of 25 the following description.

My invention is illustrated in the accompanying drawings, wherein:—

Figure 1 is an elevation partly in section of a portion of a refrigerating plant showing 30 in section the condensing jacket and coils, the compression cylinder being also in section;

Fig. 2 is an enlarged section through the condensing coils and air coils taken transversely to the plane of Fig. 1.

Referring to the drawings, it will be seen that I have illustrated a portion of a complete refrigerating plant, the entire refrigerating plant being shown in my copending application for patent above referred to. In these drawings, A designates generally the compressor, B generally the condenser, C a separator disposed within the condenser, E a receiver, and H an electric motor operat-

ing the condenser and operating the fan for 35 driving cool air through the condenser. I have not illustrated the expansion regulator nor the refrigerating coils. Inasmuch as the compressor forms the subject matter of a separate application for patent filed of even 40 date herewith, it is not believed necessary to describe the compressor.

The compressor has the usual piston 11 operating on its out stroke to draw refrigerant into the compressor by way of pipe 60 45 from the refrigerating coils and upon its in stroke to compress the heretofore expanded refrigerant and force it into the separator C, which forms the subject matter of a separate application for patent filed of even date 50 herewith and which is designed for the purpose of separating oil and other impurities from the refrigerant. From the separator, the refrigerant passes to the cooling coils 44. The refrigerant traverses these coils, being 55 gradually condensed as it does so, and passes into the receiver E, and from thence by the pipe 58 to an expansion regulator (not shown) which forms the subject matter of a separate application for patent, and thence 60 again to the refrigerating coils (not shown). The refrigerant passes from the chamber 20 of the compressor into the pipe 37, from thence into the upper end of the separator C, and by pipe 56 into the condensing coils 44. 65

Disposed around the cylinder or cylinders of the condenser is a tank or jacket 42 which is formed of thin corrugated metal and is riveted or otherwise attached at its bottom upon the flange 15 of the compressor 90 body. The side wall of the jacket is very deeply corrugated so as to give a relatively large cooling area, and extending through the interior of the cooling jacket and opening upon the outer face of the cooling jacket 95 are a plurality of thin metal pipes 43, these pipes being open at their opposite ends. Extending spirally around the cylinders of the compressor and submerged within the cooling jacket is a condensing coil 44, 100 and it will be noted from Fig. 1 that the tubes 43 are disposed between these coils and act to space the coils apart, these tubes 43 extending transversely across the jacket in the manner illustrated in Fig. 2.

Mounted in suitable bearings on one side of the compressor is a blower or air propeller 45 which forces cool air positively

against the adjacent fins of the jacket 42 and through the pipes 43 so that constant currents of cold air are caused to continually traverse these pipes 43. The crank shaft 42 carries thereon a worm wheel 46 driven by a worm 47 on a worm shaft 48. This shaft passes through a suitable stuffing box 49 in the crank case 14 and at its outer end is driven by the motor H. This shaft 10 also carries upon it the combined band and fly wheel 50, and the air propeller 45 is mounted upon a shaft 51 supported in suitable bearings, this shaft carrying upon it a band wheel 53 to which power is transmitted 15 from the band wheel and fly wheel 50 by means of a belt. A pipe 57 leads from the lower end of the coil 44 into the receiver E and from the receiver extends a pipe 58 which leads into the expansion regulator 20 (not shown). The expansion regulator is designed to control the passage of condensed refrigerating agent from the pipe 50 into the expansion or refrigerating coils and to be in turn controlled by the evaporation 25 pressure or back pressure within the expansion or refrigerating coils. A water supply pipe 66 is provided with a valve 44 to compensate for loss of water from the jacket by evaporation or from other causes. 30 The water level in the jacket 42 is kept above the level of the upper end of the condenser. By this construction a very thorough cooling of the refrigerant is obtained with a minimum amount of water. The cooling 35 jacket has deep and large corrugated spaces to give ample cooling surface, and the large number of thin metal tubes 43 running through the cooling solution and between the coils of the condenser additionally acts 40 to keep the cooling solution within the jacket at a proper temperature.

I claim:—

1. In a refrigerating compressor, a compression cylinder and means for condensing a refrigerating agent ejected from the cylinder comprising a jacket surrounding the cylinder and adapted to contain cooling liquid, a cooling coil disposed within the jacket and into which the refrigerating 45 agent from the cylinder is discharged, said jacket having transversely extending pipes of relatively thin metal opening at their outer ends upon the outside of the jacket. 50

2. In refrigerating machinery, a compres-

sor having a compressing cylinder, and means for condensing the refrigerating agent passing through the cylinder comprising a thin metallic jacket surrounding the cylinder, the jacket having its periphery deeply corrugated to provide a relatively 55 extended cooling surface, a condensing coil disposed within the jacket and into which the refrigerant from the compressor is discharged, and open-ended pipes of thin metal extending transversely across the 60 jacket and between the convolutions of the coil.

3. The combination with the compressor of a refrigerating machine having a compressing cylinder and a cooling coil into 70 which the refrigerating agent of the cylinder is discharged, of a jacket surrounding the cylinder and the coil and adapted to contain cooling liquid, said jacket having outwardly projecting fins and transversely 75 extending pipes of thin metal open at their outer ends upon the exterior of the jacket and extending all in one direction transversely of the jacket, and means for discharging air against the outer surface of the 80 jacket and into the adjacent open ends of said pipes.

4. The combination with a compressor having a compressing cylinder, and a cooling coil into which the refrigerating agent 85 from the cylinder is discharged, of a jacket surrounding the cylinder and the coil and adapted to contain cooling liquid, said jacket having transversely extending pipes 90 of relatively thin metal opening at their outer ends upon the outside of the jacket and extending transversely of the jacket and between the convolutions of the cooling coil and supporting the convolutions in spaced relation to each other. 95

5. The combination with the compressor of a refrigerating machine having a compressing cylinder, a cooling coil into which the refrigerating element from the refrigerating 100 agent is discharged, and a jacket, said cooling coil being disposed within the jacket, said jacket having pipes of relatively thin material traversing the interior of the jacket and opening at their outer ends upon the exterior of the jacket. 105

In testimony whereof I hereunto affix my signature.

PHILIP FISCHBACHER.
